W. H. ALGER

TOY

Filed May 26, 1925

William H. Alger,
INVENTOR

BY Victor J. Evans

ATTORNEY

WITNESS: Gerald Hennessy Jr.

UNITED STATES PATENT OFFICE.

WILLIAM HENRY ALGER, OF WORCESTER, MASSACHUSETTS.

DESIGN FOR TOY.

Application filed May 26, 1925. Serial No. 13,569. Term of patent 14 years.

To all whom it may concern:

Be it known that I, WILLIAM H. ALGER, a citizen of the United States of America, residing at Worcester, in the county of Worcester and State of Massachusetts, have invented a new, original, and ornamental Design for Toy, of which the following is a specification, reference being had to the accompanying drawing, forming a part hereof.

The figure is a perspective view showing my new, original, and ornamental design for toy.

I claim:—

The ornamental design for toy as shown.

WILLIAM HENRY ALGER.
